(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view similar to FIG. 1 with a guide extended; and,

FIG. 9 is a front perspective view similar to FIG. 1 with the keyboard raised.

The portions shown in broken line are for illustrative purposes only and form no part of the claimed design.
